UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

METHOD OF FORMING A HINGE LEAF.

Application filed July 24, 1924. Serial No. 727,943.

This invention relates to hinges and has particular reference to a hinge of that type having two leaves, each with a single knuckle of generally conical or dome shape, and a 5 pintle, the opposite ends of which are received in said knuckles.

The object of the invention is to provide an improved method by means of which a very strong hinge of this sort and having a pleasing appearance and smooth finish may be manufactured at a relatively low cost.

In the accompanying drawings:

Figure 1 is a view of a complete hinge and shows one embodiment which the present invention may take;

Fig. 2 is a blank of sheet metal from which one of the leaves is formed, in the present instance the left hand leaf of Fig. 1;

Fig. 3 is a view similar to Fig. 2, but showing the knuckle portion of the leaf as being tapered as by a milling operation, a step which may or may not be employed, as desired;

Fig. 4 is a sectional view taken on line 4—4 25 of Fig. 3;

Fig. 5 illustrates the outer end of the knuckle portion of the blank turned up slightly preparatory to the rolling operation;

Fig. 6 is a bottom edge view of what is 30 shown in Fig. 5 and illustrates, in dotted lines, that portion of the blank which is trimmed away;

Fig. 7 shows the knuckle as having been 35 rolled;

Fig. 8 is a bottom edge view of what is shown in Fig. 7;

Fig. 9 is a view showing the structure of Fig. 7 inverted, and illustrates the manner in which the leaf is swaged or upset adjacent the 40 knuckle;

Fig. 10 is a view of the leaf shown in Fig. 9 and looking in the direction of the arrow 10 of that figure;

Fig. 11 is a side elevational view of the 45 leaf after the first forming operation has been performed on the knuckle;

Fig. 12 is a view similar to Fig. 11, but with the attaching portion of the leaf trimmed and with the knuckle brought to final shape;

50 Fig. 13 is a top view of what is shown in Fig. 12;

Fig. 13^a is a horizontal section view through the knuckle and shank portion; and

Fig. 14 shows, more or less diagrammatically and in perspective, a device for rolling 55 the knuckle.

Referring to the drawings in detail, and particularly to Fig. 1, each of the leaves is illustrated as having an attaching portion *a*; a generally conical dome or shaped knuckle 60 *b*, and a flat shank portion *c* between the attaching portion and knuckle. *d* designates the pintle, the opposite ends of which are received by the knuckles on the respective leaves, and *e* designates a ball bearing unit 65 about the pintle and between the knuckles. This ball bearing unit may or may not be used, as desired, and the specific construction of it is not shown, as it forms no part of the present invention. In accordance with the 70 present invention, each of the leaves is formed from a sheet metal blank which is punched out to the desired shape, and then the knuckle forming portion thereof is rolled back upon itself and then suitably manipulated to bring it to the desired shape, for instance, and by preference, to an elliptical dome. As hereinabove described in detail, the process of forming each leaf is so carried out 75 that the closed end of the knuckle extends above the shank portion *c*, and the knuckle has a smooth, unbroken surface which is devoid of cracks or crevices.

In carrying out the method of the present invention, each leaf is constructed by first 80 punching from a flat sheet of metal a blank having a relatively long attaching or body portion *a'*, a shank portion *c'*, extending laterally from one of the side edges of the attaching portion, and a knuckle forming 85 portion *b'* on said shank portion. The knuckle forming portion and, by preference, also the shank portion *c'* have their lower edges 10 curved on an arc, the center of curvature of which will correspond generally 90 to the apex of the partially formed knuckle shown in Figs. 7 to 10. The upper edge 11 of the knuckle portion preferably extends above the upper edge of the shank portion, and the outer edge 12 of the knuckle forming 95 portion is inclined to the length of the attaching portion. The upper edge 11 of the knuckle forming portion is devoid of prongs, projections and the like. In the present instance, this edge is straight, and is inclined 100 upwardly and outwardly from the shank. By 105

preference, but not necessarily, the knuckle forming portion may have, at its outer upper corner, a projection or lug 13 which, when the knuckle forming portion is rolled back upon itself and then pressed to form, engages the upper corner of the knuckle forming portion adjacent the shoulder 14. The next step in the operation may be the tapering down of the knuckle forming portion from adjacent its lower edge to its upper edge. This operation may be performed by milling. Figs. 3 and 4 show the knuckle forming portion so tapered. While this operation is of advantage in that it facilitates the performance of subsequent operations, it may be omitted. The outer end of the knuckle forming portion is then bent upwardly, as indicated in Figs. 5 and 6, and then the outer edge 12 is trimmed away, as indicated by dotted lines 16 so that when the knuckle forming portion is completely rolled upon itself, the outer edge of this portion will come flat against that portion of the blank at the juncture of the shank and knuckle.

The knuckle forming portion is then turned on itself and, in this operation, the metal is rolled preferably on an arc so as to bring the knuckle to the tapered form shown in Figs. 7 and 8. Any suitable mechanism may be employed for rolling the knuckle, but, by way of illustration, I have shown, in Fig. 14, one form which this mechanism may take. In this figure, 25 indicates a base having a block 26 provided with a slot or groove 27 for receiving and holding the attaching portion of the leaf. Pivoted, as by means of a bolt 28 so as to swing in an arc generally corresponding to the curvature of the edge 10, is a die 29 having a semi-circular groove 30 in its active face. This groove preferably tapers down in radius towards the pivot of the die 29. When the die 29 is swung to the left, the surface of the groove 30 will turn and roll the knuckle back upon itself and into the shape illustrated in Figs. 7 and 8.

The leaf is then upset or bent at the juncture of the shank portion and knuckle so that the axis of the partially formed knuckle is substantially in parallelism with the plane of the attaching portion and shank portion, as shown in Figs. 9, 10. The knuckle is then swaged or pressed to final shape in one or more operations. In the present illustrative disclosure, I have shown this as being performed in two operations; Fig. 11 showing the knuckle after the first operation, and Figs. 12 and 13 showing the knuckle as having been brought to final shape by the second swaging operation. These swaging operations may be carried out by supporting the knuckle on a die, and bringing down onto the knuckle a die having a recess of the same shape and size as the shape and size to be given to the knuckle. Between the first forming or swaging operation and the final press-

ing or swaging operation, the leaf may be subjected to an annealing process. During the swaging operation, which is carried out while the knuckle is in cold condition, as distinguished from drop forging or electric welding, the metal at the small or upper end of the knuckle is caused to flow and curl in such manner as to completely close this end and provide a single line of juncture extending down from a point adjacent the apex of the knuckle to and along the end of the shank. The metal along this line is closely pressed together but is not joined or united. It will be seen from the drawings that, during this swaging operation, the knuckle throughout its height is changed from conical shape to dome shape; that is, the finished knuckle is parti-elliptical in longitudinal section. After the external surface of the knuckle has been brought to the final shape shown in Fig. 12, the opening in the knuckle is drilled to the proper diameter so as to closely receive one end of the pintle. The leaf attaching portion may be cut or trimmed to final shape and size after any of the many operations, but it is here illustrated, by dotted lines, as being trimmed after the first swaging or forming operation of the knuckle.

From the foregoing description taken in connection with the drawings, it will be seen that the leaves of my improved hinge are formed from sheet metal in a very economical and ready manner. The manufacture of the leaves requires but relatively few operations, and each of these operations may be quickly and simply carried out. Since the leaves are formed of sheet metal, they are extremely strong and, therefore, well able to withstand heavy duty. It is clear, particularly from Figs. 1, 12 and 13, that the knuckles have a smooth, unbroken exterior surface, the metal, where the edges of the knuckle forming portion are brought into engagement, being so merged and pressed together that the joints are practically invisible.

I claim as my invention:

1. The herein described method of forming a hinge leaf having an attaching portion and a dome shaped knuckle, which consists in stamping from a sheet of metal a blank having an attaching portion and a knuckle forming portion extending from the side edge of said attaching portion, rolling said knuckle forming portion back upon itself into conical form, upsetting the metal at the juncture of the knuckle to bring the axis of the knuckle substantially in parallelism with the plane of the attaching portion, and swaging the conically shaped knuckle into dome shape by forcing the knuckle, in cold condition, into a dome-shaped recess in a die.

2. The herein described method of forming a hinge leaf having an attaching portion and a dome shaped knuckle, which consists in stamping from a sheet of metal a blank hav-

ing an attaching portion and a knuckle forming portion extending from the side edge of said attaching portion, bending up the outer end of said knuckle forming portion, rolling the metal constituting the knuckle on an arc and into conical form, and swaging the partially formed conical knuckle into dome shape.

3. The herein described method of forming a hinge leaf having an attaching portion and a dome shaped knuckle which consists in stamping from a sheet of metal a blank having an attaching portion, and a knuckle forming portion extending from the side edge 15 of said attaching portion, bending up the outer end of the knuckle forming portion, trimming the outer end of said bent-up portion to provide a flat surface, rolling the knuckle forming portion back upon itself on an arc into conical form, upsetting the metal 20 at the juncture of the knuckle to bring the longitudinal axis of the knuckle substantially in parallelism with the plane of the attaching portion, and swaging the partially 25 formed conical knuckle to dome shape.

4. The herein described method of forming a hinge leaf of the character described, which consists in stamping from a sheet of metal a blank having an attaching portion, a shank 30 extending from one edge of said attaching portion, and a knuckle forming portion extending above the upper edge of said shank and having its outer edge inclined to the length of the attaching portion, said knuckle 35 forming portion having its lower edge on an arc and having at its upper outer corner a projection, rolling the metal of the knuckle forming portion in an arc back upon itself into conical form, and then swaging the partially 40 formed conical knuckle to dome shape.

5. The herein described method of forming a hinge leaf of the character described, which consists in stamping from a sheet of metal a blank having an attaching portion, a shank 45 portion extending from one edge of said attaching portion, and a knuckle forming portion on the outer end of the shank, gradually reducing in thickness the knuckle forming portion towards that end which is to form the rounded end of the knuckle, then rolling the metal of the knuckle forming portion in an arc back upon itself into conical form, and then upsetting the metal at the juncture of the shank portion and knuckle 50 to bring the knuckle with its axis in parallelism to the plane of the attaching portion, and then swaging the partially formed conical knuckle to dome shape.

6. The herein described method of forming a hinge leaf of the character described, which 60 consists in stamping from a sheet of metal a blank having an attaching portion, a shank portion extending to one side of said attaching portion, and a knuckle forming portion having its outer edge inclined to the length 65 of said attaching portion and having its lower edge curved and longer than its upper edge, said upper edge being devoid of projections and the like; rolling the metal of the knuckle forming portion back upon itself and into 70 conical form, upsetting the metal at the juncture of said shank and knuckle forming portion to bring the knuckle with its axis substantially in parallelism to the plane of said attaching portion, and swaging the partially 75 formed conical knuckle into dome shape by forcing the same, in cold condition, into a dome-shaped recess in a die.

7. The method of forming a hinge leaf, which consists in stamping from a sheet of 80 metal a blank having an attaching portion, a shank portion extending from one edge thereof, and a knuckle forming portion at the outer end of said shank portion, tapering said knuckle forming portion; slightly 85 bending the outer edge of said knuckle forming portion, trimming said bent edge, rolling the knuckle forming portion into a conical knuckle, bending the shank portion to bring the axis of the knuckle substantially 90 parallel to the general direction of the length of the attaching portion, and swaging said knuckle into dome shape.

8. The method of forming a hinge leaf, which comprises stamping from sheet metal 95 a blank having an attaching portion, a shank portion extending from one edge thereof, and a knuckle forming portion at the outer edge of said shank portion, said knuckle forming portion having its outer edge inclined relative to the length of said attaching portion and having one side edge curved and longer than the opposite side edge; tapering the shorter edge of said knuckle forming portion, slightly bending the outer edge of said 100 knuckle forming portion, trimming said bent edge, rolling the knuckle forming portion into a conical knuckle, upsetting the metal at the juncture of the knuckle and shank portion to bring the longitudinal axis of the 105 knuckle substantially in parallelism with the plane of the attaching portion, swaging said knuckle to dome shape and drilling a pintle recess in said knuckle.

STUART W. PARSONS.
